ATTORNEYS

UNITED STATES PATENT OFFICE.

CONRAD KNOTH, JR., OF RIDGEWOOD, NEW YORK, ASSIGNOR OF ONE-HALF TO JOHN T. BLADEN, OF BROOKLYN, NEW YORK.

SEAL.

Application filed September 18, 1923, Serial No. 663,380.

To all whom it may concern:

Be it known that I, CONRAD KNOTH, Jr., a citizen of the United States, and a resident of Ridgewood, Long Island, in the county of Queens and State of New York, have invented certain new and useful Improvements in Seals, of which the following is a specification.

My invention relates to seals adapted to be applied to a string, rope, cord, or wire surrounding a package or receptacle. In my co-pending application filed concurrently herewith, Serial No. 663,379, I have shown a seal of this general character and the present device while adapted for similar purposes may also serve to seal a knot tied in a cord or rope at the point of crossing between the lengthwise and cross run of the cord or rope. My object is to provide a very simple and inexpensive seal for protecting packages which are merely wrapped in paper rather than in boxes, although it will be understood that it is also adapted for use on boxes. My object is to provide a seal which will make it impossible to open a package during shipment without disclosing the fact that the same has been tampered with and it therefore serves to reduce loss claims as between shipper and consignee and between either of these and the carrier.

The present seal includes a shell which encloses and protects the knot tied in the cord or rope and it also straddles this knot at the point of crossing of the two runs of the cord or rope so that a knot can not be untied nor can one run be shifted in relation to the other.

In the drawing forming part of this application,

Figure 1 is a plan view of a package to which my seal has been applied ready for shipment,

Figure 2 is a side elevation of the package and seal,

Figure 3 is a plan view of the shell forming part of the seal,

Figure 4 is a side elevation thereof,

Figure 5 is a sectional view taken on the line 5—5 of Figure 4,

Figure 6 is a sectional view taken on the line 6—6 of Figure 1, and

Figure 7 is a perspective view of the closing strip.

The seal includes two principal members consisting of a shell for enclosing the knot

and straddling the cord or rope and a closing strip for closing the shell. The closing strip is made of a very fragile metal such as is used in the well known Edgar seal, which metal is designed to permit the strip to be bent at any point in one direction and which because of its fragile nature will immediately break if rebent.

The shell shown herein and designated by the numeral 1 comprises a cylindrical wall 65 2 closed at one end by the dome-shaped cap 3 forming a chamber 4 of sufficient size to enclose the knot 5 which is tied in the cord or rope which surrounds the package 6 this knot in the illustration shown herein, being 70 formed at the intersection of the cross run 7 and the longitudinal run 8 of the cord or rope.

Preferably, the dome or cap 3 is provided with oppositely arranged apertures 9 of just 75 sufficient diameter to permit the free ends of the rope to be separately passed therethrough for a purpose which will appear hereinafter. The shell is provided with oppositely disposed slots 10 near the closed end 80 to receive the closing strip therethrough. The open end of the shell is provided with two oppositely arranged vertical slots 11 to receive therein one run of the rope and it is provided with two oppositely arranged 85 vertical slots 12 to receive the other run of the rope, the slots 11 being preferably arranged in a direction at right angles to the slots 12. The bottom edge of the shell is cut away at opposite sides along the lines 13 so 90 that the portions 14 extend below these edges 13. The closing strip shown in Figure 7 is illustrated as provided with weakened points to facilitate bending of the strip at three different locations. These easily 95 weakened points may consist of side notches 15 in the strip or of cross slots or partial cuts 16 or both of these as desired.

Operation.

The package is tied with the rope arranged crosswise and lengthwise to provide the runs 7, 8 and the ends of the rope are brought together at the point of intersection of these two runs and the knot 5 is 105 then tied in the rope leaving short lengths extending beyond the knot. The shell 1 is placed over the knot 5 and over the rope in such manner that one run of the rope is received in the vertical slots 11 and the 110

other run is received in the vertical slots 12 and the free ends of the rope may be carried out through the apertures 9 in the cap and an external knot 17 may be tied with these ends to hold the cap in place while the closing strip is being applied. The closing strip is then inserted through slots 10 so that it passes across the shell above the knot 5. The strip is then bent downwardly at 20 and it is again bent at right angles at the point 21 so that it passes across under the edges 13 at 22 and between the lower projections 14 of the shell. The strip is again bent at right angles at the point 23 to form an up-turned lip 24 on the opposite side of the casing to the vertical portion 25. The seal is now applied and the package may be shipped without fear of its being opened without leaving evidence of the fact. If any attempt is made to rebend the closing strip at the point 23 to open the lower end of the shell, the strip, because of its fragile nature, will break at this point. It can not be moved sidewise because of the lower projections 14 and any attempt to bend it downwardly away from these projections will cause the strip to be broken at the point 21. If an attempt is made to rebend the up-turned end 24 in order to withdraw the strip to the left in Figure 6 the strip will break at the point 23. As the strip and shell enclose the knot 5 access can not be had to the knot for the purpose of untying it for the reasons thus described.

In order that the closing strip may not be removed surreptitiously and then replaced by another one, the individual closing strips may be numbered or lettered or otherwise 40 individually marked and the individual mark may be placed on the invoice furnished the consignee so that when the latter receives the package referred to in the invoice, if the closing strip bears the same mark as that indicated in the invoice and the strip is unbroken, the consignee may be certain that the package has remained unopened from the time it left the hands of the consignor. It will be apparent that the present seal 45 may be very quickly applied to packages and that it is a positive protection against theft of the contents of the package. It will be understood that the closing strip

is destroyed when the consignee opens the seal but the shell remains intact and may be used over again.

Having described my invention, what I claim is:

1. A seal of the class described comprising a shell adapted to enclose a knot tied in a 60 rope or cord, said shell having an open end to receive the knot therein and having a plurality of slots extending upwardly from said open end to receive different runs of a cord or rope arranged at an angle 65 to each other, and a closing strip of easily breakable material adapted to be attached to said shell to close the shell for the purpose of sealing the knot therein.

2. A seal of the class described comprising 70 a shell having a closed end and an open end to receive therein a knot in a cord or rope, said shell having slots therein adjacent the closed end, and a closing strip of easily breakable material adapted to be 75 inserted in said slots and adapted to be bent downwardly and across the open end of said shell to seal the knot therein.

3. A seal of the class described comprising a shell having a closed end and an open end 80 to receive therein a knot in a rope or cord, said shell having slots therein adjacent the closed end, and having projections at its open end, and a closing strip of easily breakable material adapted to be passed 85 through said slots and to be bent downwardly and across the open end of said shell between said projections for the purpose of sealing the knot in said shell.

4. A seal of the class described comprising a shell having a closed end and an open end said closed end having apertures through which the ends of a cord or rope may be passed, said shell having slots 90 therein below said apertures and angularly disposed in relation thereto, said shell having projections on its open end, and a closing strip of easily breakable material adapted to be passed through said slots and to be bent downwardly and across 95 the open end of said shell between said projections for the purpose of sealing a knot in said shell.

Signed at the city, county and State of New York, this 1st day of September, 1923.

CONRAD KNOTH, JR.
